[57] CLAIM

The ornamental design for a tablet counting tray, as shown and described.

DESCRIPTION

FIG. 1 is a top left perspective view of a tablet counting tray showing my new design;

FIG. 2 is a bottom right perspective view thereof;

FIG. 3 is a front perspective view thereof; and

FIG. 4 is a top rear perspective view thereof.

The sides not shown in the perspective views are similar in form to those shown.

FIG. 1

FIG. 2

FIG. 3

FIG. 4
